TOY

Jack J. Levin, Baltimore, Md.

Application October 9, 1933, Serial No. 692,791

9 Claims. (Cl. 46—37)

This invention relates to toys and has particular reference to a playing device for children of infant age. This playing device comprises a tray having attached thereto one or more individual toys which may be grasped and moved by a child when the tray is secured to any convenient object, such as a chair, crib or perambulator, within the child's reach and which will automatically return to the desired normal position on the tray when the child releases its grasp.

Toys of this class heretofore manufactured, while satisfactory from the standpoint of the sense of touch, have been but partially satisfactory from the standpoint of sense of sight and most unsatisfactory from the standpoint of the sense of hearing, because no adequate means were provided for regulating the automatic return of the toys to their normal positions on the tray when the child released its grasp. Without such regulation, the toys would fly back to the tray as soon as released by the child and strike the tray with a frightening sound, thus alarming and startling the child instead of amusing it and keeping it contented.

Among the objects of this invention is the provision of a playing device as above described with means for regulating and controlling the automatic return of the toys to their normal positions on the tray. A further object of this invention is to provide automatic means for causing the toys, as they return to their normal positions on the tray, to undergo novel motions and movements which serve to amuse and arrest the attention of the child playing with the toy. A still further object of this invention is to provide means whereby amusing and pleasing sound effects are produced by the device while the toys are automatically returned to their normal positions on the tray.

Other, further and more specific objects of this invention will become readily apparent to persons skilled in the art from a consideration of the following description when taken in conjunction with the accompanying drawing wherein:

Fig. 1 is a longitudinal vertical section through the playing device.

Fig. 2 is a bottom plan view of the device with the bottom cover removed, a part of the device being broken away to illustrate internal construction.

Fig. 3 is an enlarged fragmental detail view in section of a convenient means for controlling the air vent in the cylinders shown in Figs. 1 and 2.

The device comprises the casing 1 having apertures 2 on the top through which pass the strings

or other flexible connections 3. The outer ends of these strings are fastened to toys 4 and 5 and the inner ends are fastened to the drums 6 about which they are wound. These drums are keyed to the axles 7 which are rotatably supported by inner strips 8 connected to the side walls of the casing 1. A string or other flexible connection 9 is also secured at one end to each axle 7 and at the other end to a movable piston 10 within the cylinder 11. The other end of the piston is connected to a spring 12 which is fastened at 13 near the closed end of the cylinder 11. If desired, the spring 12 may be secured at or near the open end of the cylinder instead of near the closed end, in which case the spring will be compressed instead of being extended as the piston moves to the open end of the cylinder.

When any of the toys 4 and 5 are moved away from the casing the string attached thereto will rotate the drum to which it is fastened and simultaneously rotate the axle 7 supporting the drum. Rotation of the axle will cause the string 9 to wind thereon and pull the piston 10 forward against the tension of the spring 12. Upon releasing the toy, it will be automatically returned to its normal position on the casing by the spring acting through piston 10, string 9, axle 7, drum 6 and string 3.

As a means for regulating and controlling the automatic return of the toy to its normal position in the device, the cylinder is provided with bores 14 and 15 which serve as air vents. By adjusting the sizes of these bores the speed of the automatic return movement may be regulated and controlled by the dash pot construction shown herein. The cylinders 11 may have one or more air vents, and the size of each vent is adapted to the kind of movement which the toy is to undergo during its automatic return after being released. For example, in Fig. 2 the bore 15 is larger than the bore 14, and the piston on its return movement will force air through both of these bores and travel rapidly until it passes the bore 15, after which air will escape only through the bore 14 and the piston will move much slower, and the piston and also the toy will proceed gradually to the position of rest, without objectionable noise or shock. The piston 10 will travel through a shorter distance than the toy because the string 9 connecting the former winds upon the axle 7 of small diameter while the other string 3 connecting the toy winds upon the drum 6 of large diameter. The air escaping from the cylinder through any one or more bores may be made to operate a whistle or other sound producing device

16, which will add very much to the value of the device in amusing the child and arresting its attention.

Very pleasing sound effects may also be produced 5 with a device of this character by having one or more fingers 17 extending from the drum 6, which fingers are made to strike one or more prongs suitably attached to the device when the drum rotates.

10 The perforations in the tube 11 may be of fixed size or else adjustable by suitable means such as the needle device 18 shown in Fig. 3.

In order to fasten this device to a chair, table, 15 crib, etc., I have provided the straps 19. It will be seen that the bores 2 in the top of the casing serve as a guide for the string, and the top of the casing may be raised so as to form the projections 20 to provide seats for the toys and to strengthen the top at the perforations.

25 The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

30 1. In a play device, a casing, a drum within said casing fastened on a rotatable axle, a flexible connection having its inner end secured to said drum and passing through a guiding aperture in the top of said casing, a toy fastened to the outer end 35 of said flexible connection, a cylinder closed at one end, a spring having a part in fixed position, a piston within said cylinder connected to said spring, another flexible connection extending from said piston to the said axle and means for controlling the escape of air from said cylinder when the piston moves toward the closed end of said cylinder.

40 2. The combination claimed in claim 1, having a vent in the cylinder as the means for controlling the escape of air from the cylinder.

45 3. The combination claimed in claim 1, having an adjustable vent in the cylinder as the means for controlling the escape of air from the cylinder.

50 4. The combination claimed in claim 1, having a plurality of vents of different size in the cylinder as the means for controlling the escape of air from the cylinder, the smallest vent being positioned nearest the closed end of the cylinder.

5. The combination claimed in claim 1, having a vent in the cylinder as the means for controlling the escape of air from the cylinder together with a sound producing device for operation by the air passing through said vent.

6. In a play device, a casing, a cylinder closed at one end, a spring having a part in fixed position, 10 a piston within said cylinder connected to said spring, a toy movable to and from said casing, means comprising a flexible connection passing through a guiding aperture in said casing for transmitting the movement of said toy to said piston and means for controlling the escape of 15 air from said cylinder when the piston moves toward the closed end of said cylinder.

7. In a play device, a casing, a cylinder closed at one end, a spring having a part in fixed position, 20 a piston within said cylinder connected to said spring, a toy movable to and from said casing, means comprising a flexible connection passing through a guiding aperture in said casing for transmitting the movement of said toy to said piston, means for controlling the escape of air 25 from said cylinder when the piston moves toward said cylinder and means for producing a distinctive sound when the piston returns toward the closed end of the cylinder.

30 8. In a play device, a casing, a toy movable to and from said casing, a spring, means comprising a flexible connection passing through a guiding aperture in said casing for transmitting the movement of said toy to said spring and means for controlling the return of said spring to its normal position and thereby controlling the return 35 of said toy to said casing.

9. In a play device, a casing, a toy movable to and from said casing, a drum within said casing fastened to a rotatable axle, a flexible connection having its inner end secured to said drum, and passing through a guiding aperture in the top of 40 said casing and having its outer end connected to said toy, a spring, means for transmitting the movement of said toy to said spring and means for controlling the return of said spring to its normal position and thereby controlling the return 45 of said toy to said casing.

JACK J. LEVIN.
